UNITED STATES PATENT OFFICE

2,004,755

DUMP WAGON

Theodore C. Harvey, Philadelphia, Pa.

Original application February 8, 1933, Serial No. 655,744. Divided and this application October 14, 1933, Serial No. 693,547

2 Claims. (Cl. 298—7)

This is a divisional application of a copending application filed February 8, 1933, Serial No. 655,744.

This invention relates to dump wagons, the broad object of said invention being to provide a wagon of the class described, which is capable of various operations in order to expedite and facilitate the discharge of the load therefrom in a manner most convenient to the operator as well as minimizing traffic obstruction.

One object is to provide a dump wagon having a bottom discharge and capable of being automatically emptied or unloaded, partially or wholly from either side of the wagon body.

Another object in view, is to provide for emptying the load partially or wholly from the bottom.

Another object in view, is to provide for directing the discharging load toward either side, bottom, front and rear or practically in almost any direction downwardly or inclined from the bottom discharge opening of the load body.

Another object in view, is to provide in connection with a body having the characteristics above referred to, means for vertically raising and lowering the body in relation to the truck frame, without interfering with the discharge of the load under the advantageous conditions above enumerated.

Another object in view, is to provide means for ground control of the revolving chute with the body either elevated or lowered.

Another object in view, is to provide for the adequate height of the discharge outlet for ordinary delivery of the load, reserving the elevation means for unusual requirements in height and distance in conjunction with extension chutes of transferring the load to other vehicles, over fences, onto lawns, etc.

With the above and other objects in view, the invention consists substantially in the combination, construction, location and relative arrangement of parts, all as will appear more fully hereinafter, as shown in the accompanying drawings and as finally pointed out in the appended claims.

In the accompanying drawings:—

Fig. 1 is a side elevational view of a dump wagon constructed in accordance with and embodying the principles of the present invention;

Fig. 2 is a vertical, longitudinal section through the dump wagon;

Fig. 3 is a plan view of the dump wagon em-

bodying the present invention, the fore and aft standards being shown in horizontal section;

Fig. 4 is a front end elevational view of the dump wagon showing the truck body or double platform arrangement, skeleton body supports, load doors and outlet controls and revolving chute discharge outlet, the forward elevating standard being shown in cross section;

Fig. 5 is a detail perspective view of the detachable revolving chute outlet;

Fig. 6 is a similar view of the flared extension chute; and

Fig. 7 is a detail perspective view of one of the corrugated chute supporting rails.

Referring now more particularly to the drawings, it will be observed that the wagon body or receptacle for the load as shown is of inverted frusto-pyramidal shape. While this is the preferable shape, it will be understood that the invention or inventions to be described more fully hereinafter are equally applicable to bodies or load receptacles of different shapes than that shown in the drawings, the principal characteristic of the body with which this invention is concerned being that the side walls thereof converge downwardly toward an opening in the bottom of the body. In the drawings the load receiving body is designated generally by the reference numeral 10, the centrally disposed bottom opening or outlet having suitably secured to the perimetral edge thereof a frame member provided with intersecting division strips 11 and 12 whereby to provide a plurality of substantially equal-sized openings 13, each of which constitutes an individual discharge outlet. It will be apparent that by the provision of the four discharge outlets, the material contained in the body may be discharged through any one or more of the said discharge outlets.

As is described in my copending application above identified, each of the discharge outlets 13 thus provided in the bottom of the body is adapted to be opened and closed by a horizontally arranged slidable closure member 13^a, these closure members being all movable in directions extending longitudinally of the main body 10. The arrangement of these closure members 13^a and the means for effecting their operation will not be described herein. Should a more detailed description thereof be desired, reference is made therefor to my copending application Serial No. 655,744.

As appears most clearly in Figure 1, the main body 10 rests upon and is directly supported by a foundation board or platform 14 having

formed therein an elongated central opening 15. This platform 14 is adapted for vertical movement together with the main body 10 supported thereby by means to be described hereinafter. 5 The platform 14 is, of course, disposed in a substantially horizontal plane above the vehicle frame 16. The fore and aft ends of the vehicle frame side members are preferably in the form of partially boxed-in sections the vertical side 10 walls of which are each provided with a centrally disposed opening 17. Disposed between the openings 17 in the opposite side walls of the vehicle frame and suitably secured to the bottom end of the main body 10 is a revoluble discharge chute 20, the vehicle frame 16 being of a sufficient depth to allow for the desired vertical and rotative movement of the discharge chute 20.

The vehicle frame 16 is of substantially rectangular formation, thus permitting not only a vertical movement of the discharge chute 20 therewithin but also a circular movement thereof when the body 10 is in lowered position, the openings 17 in the side walls of the vehicle frame being of sufficient length and depth as to permit the free movement therethrough of the outer end of the discharge chute.

As appears most clearly in Figure 4, the free end of the discharge chute 20 extends somewhat beyond the side limit of the vehicle frame when the chute is directed into position for discharging the load from the side of the vehicle, thereby facilitating the filling of receptacles from either side of the vehicle when the main body 30 10 is in its lowered position. At the same time, by so arranging the discharge chute that its outer end extends through the opening 17 of the vehicle frame, the attachment of the short flared extension chute 21, such as is shown in Figure 6, is greatly facilitated.

As appears most clearly in Figures 1, 4 and 5, the revoluble discharge chute 20 is provided at opposite sides of the discharge end thereof with a pair of chains 22 to which are adapted to be respectively hooked the hooks 23 arranged upon either side of the flared end of the extension chute 21.

Suitably secured to the upper end of the circular body of the discharge chute 20 is an annular rack bar or worm gear 24 which is adapted for meshing engagement with and actuation by a worm 25 fixed to a transverse shaft 26 the opposite ends of which are journalled, as at 26a (see Figures 3 and 4), to the foundation board or platform 14. Keyed to one end of this shaft 26 is a bevel gear 27 in mesh with a bevel gear 28, the latter being non-rotatably but slidably secured to a vertically extending rotatable shaft 30. This shaft 30, which is provided with a longitudinally extending groove 29 within which the bevel gear 28 is slidably keyed, is suitably encased within a supporting tube or casing 31 which is securely held in position at its upper end by a bracket 32 (see Figure 3) mounted upon the side of the main body 10.

Secured to the lower end of the shaft 30 is an operating handle 33 for effecting the desired rotation of the revoluble discharge chute 20 from the ground regardless of the vertically adjusted position of the main body, it being apparent that as the said body is raised or lowered, the transverse shaft 26 is correspondingly moved therewith as is the bevel gear 28, the latter being constantly in mesh with the bevel gear 27. Preferably, the lower end of the rotatable shaft

30 is journalled within a bracket 34 (see Figure 4) mounted upon the side edge of the vehicle frame 16.

Mounted upon the vehicle member 16 of the vehicle truck at the fore and aft ends thereof are a pair of body elevating means 35 and 36. Inasmuch as these means are described in detail in my copending application aforesaid and in view also of the fact that any suitable elevating means may be employed to elevate the body 10 as desired, the construction of the particular elevating means shown will not be described herein in detail, it being sufficient for the present purposes merely to point out that each of these elevating means embody a standard 37 within which is journalled a vertical screw 38, the latter operating upon a block 39 to raise and lower the same. The blocks 39-39 are in turn respectively connected to opposite ends of the foundation board 14 through suitable cables 40-40, each of which passes over suitably journalled pulleys 41 and 42.

Preferably, the upper ends of the fore and aft standards 37-37 are preferably respectively covered by the caps 43 retained in position by means of the screw bolts 44. These standards 37-37 are respectively slotted, as at 45, in the faces thereof which present toward each other in order to permit the free vertical movement of the substantially T-shaped extensions 46 provided at either end of the foundation board or platform 14, these extensions being retained within the standards 37-37 and guided during the vertical movement of the platform by the vertically extending ribs 47 which define the vertically extending slots 45 in the standards. Preferably, the standards are each strengthened and supported by side braces or ribs 48 and 49.

Referring now more particularly to Figures 1 and 2, it will be observed that the mechanism for operating the bottom trap doors 13a includes a forward pair of transversely extending shafts 50 and 51 and a rearward pair of transversely extending shafts 52 and 53, each of said shafts 45 being suitably journalled upon the bottom surface of the foundation board or platform 14. The forward shafts 50 and 51 respectively have fixed thereto the pinions 54 and 55, while the rearward shafts 52 and 53 have respectively 50 fixed thereto the pinions 56 and 57, it being observed that the pinions 54 to 57 are relatively so located that they respectively engage the longitudinally extending rack bars 58 which are respectively secured to the several trap doors 55 13a (see Figure 2). Secured to the opposite outer extremities of the transversely extending shaft 50 are a pair of hand wheels 59, the transversely extending shafts 51, 52 and 53 being similarly provided at their opposite extremities 60 with hand wheels 60, 61 and 62, respectively. It will be apparent that by virtue of these hand-operated transversely extending shafts and the four sets of hand wheels arranged to either side of the vehicle the opening or closing of any one of the trap doors by an operator stationed at either side of the vehicle is facilitated.

Still another means is provided for opening and closing the bottom trap doors 13a, this latter means including a plurality of flexible cables 63 which are respectively terminally attached to the eyes 64 of the rack bars 58, the cables 63 being respectively passed over the pulleys 65 which are journalled in the foundation board or platform 14, the free ends of the several cables 75

63 being looped, as at 66, to provide hand grips by means of which the operator, standing upon the ground, may pull one or the other of the several cables 63 to open the desired trap door or doors 13^a.

As appears most clearly in Figures 1 and 2, the main body 10 has pivotally mounted at opposite sides thereof, as at 68, a pair of laterally spaced thrust arms 69, one such arm being provided for each cable 63. Each of the thrust arms 69 terminates in arcuately curved portions having an arcuated slot 70 within which is adapted to be projected a pin 71 provided on each rack bar 58. A contractile spring 72 connects each thrust arm to the main body 10, these springs serving normally to pull the several thrust arms 69 toward the body and in so doing causes the trap doors 13^a to be respectively moved into closed position, this latter action being effected through the slot and pin connection between each thrust arm 69 and its associated rack bar 58.

Still other means may be employed for selectively operating the trap doors 13^a, one such additional means being described in my copending application aforesaid to permit the operation of the trap doors from the cab of the vehicle. As appears most clearly in Figure 7, a supporting rail 73 is provided for use with the extension chute 21 or the like when it is not desired to employ the revolute discharge chute 20. This chute supporting rail 73 is provided with a serrated or corrugated central section, the ends of this rail being adapted for removable securing to the bottom frame defining the bottom discharge outlet of the main body. As appears in Figure 7 this chute supporting rail may be in the form of a straight section the opposite ends of which are provided with an upwardly projecting supporting arm, the chute so formed being adapted for connection to the said bottom frame so that the corrugated edge thereof extends either longitudinally or transversely across any longitudinally or transversely arranged pair of the discharge openings 13. If desired, the chute supporting rail may be rectangular, circular or other such continuous outline with means for attaching the same to the bottom frame of the discharge outlet in such manner that a chute may be suspended therefrom in any one of a number of positions, thereby affording communication between the chute and any desired one of the discharge outlets 13. It will be understood that the serrations or corrugations 74 formed in the chute-supporting rail, when the chute hooks 75 (see Figure 6) are engaged therewith, prevent lateral displacement of the supported end of the chute. It will also be understood that the chute-supporting rail, be it of the type shown in Figure 7 or of the rectangular shape or curved shape, when properly mounted in position provides for intermittent use of a chute when the vehicle is being employed principally as an ordinary central drop load dump wagon. When the chute or supporting rail 73 is so employed, the revolute discharge chute 20 is, of course, removed from the load receiving body.

As has already been observed, the extension chute 21 is provided with hooks 75 at its rear end which are adapted not only for engagement with the supporting rail 73 aforesaid but also for engagement with a rail 76 carried by and extending across the bottom of the outwardly

extending section of the revolute discharge chute 20. The side walls of the extension chute 21 are flared toward their rear end, the flared portions 77 of these side walls being respectively provided with the laterally projecting hooks 23 respectively adapted for engagement with the chains 22 with which the revolute chute 20 is equipped. The extension chute 21 is preferably employed when it is desired to discharge the load or portions thereof into receptacles to be filled, coal holes, troughs, tram cars and the like, all of which are located upon the ground when the body 10 is lowered. The end hooks 15 on the extension chute 21 are employed principally when the body is elevated and a long chute is required. The extension chute 21 being narrower in its main body portion and flared at its intake or receiving end and being further provided with an end wall 79 extending between and interconnecting the oppositely flared side walls, constitutes a receiving member for the material being discharged wherein spilling of said material is greatly minimized. Preferably, the flared intake end of the extension chute is of sufficiently large dimension to embrace the hole of the discharge opening which is covered by the four bottom trap doors 13^a, thus permitting the use of this extension chute with or without the revolving discharge chute 20. Preferably, the discharge end of the extension chute 21 is provided with handles 80 or the like for facilitating its manipulation into the desired position.

As appears most clearly in Figures 1 and 5, the revolute chute discharge 20 is provided with a circumferentially extending downwardly turned flange 81 the bottom edge of which constitutes a continuous circular track for rotatably supporting the discharge chute upon rollers 82 which are suitably journalled in brackets 83 bolted or otherwise secured to the bottom surface of the foundation board or platform 14. When it is not desired to employ the revolute chute discharge, the same is readily removed from its operative position as shown in Figure 1 simply by loosening several of the bracket bolts thereby permitting the rollers 82 to be moved out of engagement with the track 81 and consequently permitting the removal of the revolute discharge chute bodily from the vehicle.

In order to conserve space and prevent spilling in connection with the use of the revolute chute discharge 20, a demountable frame 84 is employed (see Figure 2), this frame being provided with sloping side walls which converge downwardly to form a bottom opening disposed substantially in a horizontal plane lying below the upper edge of the discharge chute 20. This frame, which practically encompasses the four discharge openings 13^a, is secured in position to cross pieces within the foundation board or platform 14 by means of bolts 85. When it is desired to employ the body for regular drop load purposes, the frame 84 and with its associated revolute chute discharge 20 are readily removed by the simple expedient of removing the bolts 85.

From the foregoing description, when considered in connection with the accompanying drawings, it will be observed that a vehicle has been produced having an enclosed revolute chute discharge which permits of a wide range of service, particularly when it is employed in connection with the flared extension chute, spilling of the discharge load being reduced to a minimum.

veritable minimum. Furthermore, the revolute chute discharge permits the load to be discharged while the body 10 is in a raised or lowered position, it being further possible to direct the discharge load to a point either within or without the external lines of the vehicle frame. This is a particularly desirable feature in all such instances wherein it is necessary that the discharge load be clear of the vehicle wheels so as not to hinder the free movement of the vehicle in either direction once the load has been discharged. Furthermore, when the revolute chute discharge is removed, the load may be discharged directly from the bottom of the main body or it may be directed to either side thereof by way of an extension chute suitably supported by the chute rails which are adapted to be attached to the bottom of the body as hereinbefore described.

20 The body is self-emptying either in its elevated or lowered position, it being apparent that the entire body may be raised or lowered either by hand or by motor without spilling any of the load. Also, the outlet trap doors in the bottom of the main body are adapted to be operated from the seat selectively and individually, or in pairs, or they may be all operated simultaneously, all without affecting the operation of the revolute chute or its associated parts.

30 It will be understood, of course, that the invention is susceptible of various changes and modifications which may be made from time to time without departing from the real spirit or general principles thereof and it is accordingly intended to claim the same broadly, as well as specifically, as indicated in the appended claims.

What is claimed as new and useful is:—

1. A dump wagon of the character described comprising, in combination, a main body constituting the load receptacle, said main body being provided with a bottom discharge opening, a supporting platform for said main body, said platform being adapted for vertical movement whereby to raise or lower said main body, a revolute chute discharge member operatively associated with said main body and disposed immediately beneath the bottom discharge open-

ing thereof, said chute discharge member being provided with a radially extending chute extension, a circular rack secured to the peripheral edge of the body of said chute discharge member, a laterally extending shaft journalled in said platform and having a worm gear in mesh with said circular rack for effecting the rotation thereof in one direction or another, said laterally extending shaft being extended outwardly beyond one side edge of said platform 10 and provided at the outer extremity thereof with a bevel gear, a vertically extending shaft journalled upon the side of said main body, a bevel gear carried by said vertical shaft and arranged for slidable movement therewith but 15 fixed against rotation with respect thereto, said last-mentioned bevel gear being in mesh with said first-mentioned bevel gear, and means for rotating the said vertical shaft in one direction or another whereby to effect the rotation of said 20 revolute chute member in one direction or another, said bevel gears being maintained in meshed engagement with each other throughout the vertical movement of said platform and the main body supported thereby. 25

2. A dump wagon of the character described and comprising, in combination, a main body constituting the load receptacle, said body being provided with a bottom discharge opening, a revolute chute discharge member operatively 30 associated with and carried by said main body immediately beneath said discharge opening, said chute discharge member being provided with a circular rack, a vertically movable platform upon which said main body is supported 35 whereby to elevate the latter with respect to the ground, gear means operative upon said circular rack for effecting the rotation of said discharge member to present the chute thereof in any desired direction, means accessible from 40 the ground and to one side of the load body for actuating said gear means, and means included in said gear means for permitting the actuation thereof while said main body is in its fully lowered or fully raised position or in any intermediate elevated position. 45

THEODORE C. HARVEY.
